UNITED STATES PATENT OFFICE.

ROSCOE A. BROOKS, OF CHICAGO, ILLINOIS.

TOY PISTOL.

SPECIFICATION forming part of Letters Patent No. 767,380, dated August 16, 1904.

Application filed June 3, 1903. Serial No. 159,839. (No model.)

To all whom it may concern:

Be it known that I, ROSCOE A. BROOKS, a citizen of the United States of America, and a resident of Chicago, in the county of Cook and State of Illinois, have invented certain new and useful Improvements in Toy Pistols, of which the following is a specification.

The main object of my invention is to provide a simple and inexpensive form of toy in which fire-crackers of the common form may be safely discharged. I accomplish this object by the device shown in the accompanying drawings, in which—

Figure 1 is a side elevation of a toy pistol constructed according to my invention. Fig. 2 is a vertical longitudinal section of the same, partly broken away. Fig. 3 is a transverse vertical section of the same on the line 3 3 of Fig. 1.

20 In the form shown the pistol consists of a cylindrical barrel 1, having a cylindrical bore or aperture 2 extending longitudinally through same from end to end. A handle 4 extends rearwardly below the barrel 1 and is integral with the under face thereof. A breech-block 5 is mounted on the pivot 6 and is movable across the rear end of the aperture 2. By pivoting the block 5 at its upper end it will be observed that it will move across the

30 rear end of the barrel by gravity, thus insuring the closing of the barrel. The pivot 6 forms a part of the lug 7 on the barrel 1 and is integral with said barrel. The pivot 6 is preferably made longer than the thickness of

35 the block 5 and has a shoulder 6' at its free end, which bears on the outer face of the block 5 and normally holds same in position on the pivot. The block 5 is provided with an aperture 8, fitting the pivot 6 and suitably extended

40 at one side to permit the passage of the shoulder 7 when the block 5 is being placed upon the pivot 6. The block 5 is provided with an extension 9, which is adapted to enter the recess 10 in the handle 4 and secure the block 5 firmly when same is in its closed position

45 across the aperture 2. A channel 11 is cut transversely across the rear end of the barrel 1 and forms a passage for the fuse of a fire-cracker seated in the bore 2. In the drawings the fire-cracker is indicated by the dotted

circle 12 and the fuse by the dotted lines 13 in Fig. 3.

The parts of the device are of such form that they may be cast complete and assembled without machine-work of any kind, making 55 the device inexpensive to manufacture.

In operation the parts are assembled by passing the block 5 over the pivot when said block is held in the position shown by dotted lines in Fig. 3. The part 5 may then be turned 60 to any of the positions shown by full lines in the drawings and will be secured to the barrel 1 by the pivot 6. To load the pistol, the block 5 is moved to the position shown in Fig. 3 and a fire-cracker is inserted into the rear 65 end of the aperture 2. The fuse 13 is then bent over so as to extend along the channel 11, and the block 5 is moved across the aperture until the extension 9 is seated in the recess 10. When the fuse is now lighted, the fire-cracker 70 will be discharged within the barrel and in a safe manner, since the block 5 securely closes the rear end of the aperture 2 and prevents parts of the fire-cracker from flying rearwardly.

75 It will be seen that some of the details of the construction shown may be altered without departing from the spirit of my invention. I therefore do not confine myself to such detailsexcept as hereinafter limited in the claim. 80

What I claim as my invention, and desire to secure by Letters Patent, is—

A pistol comprising a barrel, a lug formed integral with the upper side thereof and having its rear face flush with the rear end of the 85 barrel, a rearwardly-projecting pivot secured to said lug, a handle formed integral with the under side of the barrel, and extending rearwardly therefrom, said handle being formed in its upper face with a recess, and a breech-block mounted on said pivot, said block being adapted to move across the rear end of said barrel, and an extension on the lower end of said block normally received in the recess of said handle.

95 Signed at Chicago this 1st day of June, 1903.

ROSCOE A. BROOKS.
